UNITED STATES PATENT OFFICE.

ALFRED LAURENTIUS PETERSON, OF CLIPPER MILLS, CALIFORNIA.

ANNUNCIATOR.

No. 802,111.

Specification of Letters Patent.

Patented Oct. 17, 1905.

Application filed April 10, 1905. Serial No. 254,754.

To all whom it may concern:

Be it known that I, ALFRED LAURENTIUS PETERSON, a citizen of the United States, residing at Clipper Mills, in the county of Butte 5 and State of California, have invented new and useful Improvements in Annunciators, of which the following is a specification.

My invention is an annunciator for telephones, and more particularly a device to indicate that a call has been received.

The invention comprises a drop-shutter which is actuated by the hammer of the call-bell, so that when a call is received during the absence of the person that fact will be visually indicated upon his return. Instead of a drop-shutter a card or slate can be used in connection with a pencil which makes a dash on the card or slate when the call-bell rings and thus indicates that a call has been received. Means 15 are also provided for disconnecting the shutter-actuating mechanism from the bell to render the device inoperative when so desired and without removing it from the telephone instrument.

Improved details in the construction and arrangements of the various parts of the invention will be apparent from the detailed description hereinafter, reference being had to the accompanying drawings, in which—

Figure 1 is a front elevation of the invention in position on the telephone-receiver box, and Fig. 2 is a side elevation thereof. Fig. 3 is a top plan view, the drop-shutter being removed. Fig. 4 is a central vertical section. Fig. 5 is a rear elevation. Fig. 6 is an edge view of the drop-shutter and its supporting-plate. Fig. 7 is a front elevation of the invention, showing the modified form in which a cardboard or slate is used on which the call 30 is recorded by a pencil.

Referring specifically to the drawings, 10 denotes the door of a telephone-receiver box, and 11 the call-bell. A plate 12 is clamped to the door, on the outside thereof, by brackets 14 and 15, which are spaced from each other by a block 16 extending therebetween. The outer ends of the block are reduced and threaded and extend through the brackets, the parts being securely fastened together by 45 nuts 17, which are screwed on the projecting threaded ends of the block. At the top and bottom of each bracket are outwardly-extend-

ing stems 18, which extend through holes in the plate 12 and are threaded on their outer ends to receive clamping-nuts 19. The bottom of each bracket is also formed with a shoulder 20, which fits over the inner top edge of the door. Set-screws 21 are threaded to the brackets at the top thereof. The brackets 14 and 15 and the plate 12 are securely clamped to the door upon tightening up the nuts 19. The set-screws 21 are extended against the back of the plate, and they can be set and regulated according to the thickness of the door.

At 22 is indicated a holder for the shutter, to be described hereinafter. The holder is slidably mounted on the stems 18, its corners being shaped to fit thereon. An undercut groove 23 is made in the back of the holder, 55 in which groove a frame 24 is placed. In said frame a screw 25 is loosely secured, which screw is threaded through the block 16 and has on its outer end a finger-button 26. When the screw is rotated, the holder will slide back 60 and forth on the stems 18. A cleat 27 extends across the holder in front along the bottom and sides thereof, and the holder also carries spring-fingers 28 for a purpose to be described hereinafter.

The plate 12 has an undercut vertical slot 29, through which the pivot-screw 30 of the lever 31 extends. The bolt is retained in the slot by its head 32, which fits in the undercut portion of the slot. A sleeve 33 is mounted 85 on the pivot-screw outside the slot and extends through the bearing 34 of the lever. The inner end of the sleeve is enlarged, as at 35, which fits against the plate 12 and acts as a washer to space the lever 31 therefrom. The 90 opposite end of the sleeve extends slightly beyond the bearing 34. A nut 36 is screwed on the outer end of the pivot-screw against the projecting end of the sleeve. By this construction when the nut 36 is screwed tight 95 the pivot-screw will be securely fastened in the slot without binding the lever, and thus preventing it from swinging freely. The pivot-screw can be readily adjusted up and down in the slot by simply loosening the nut 36. 100 The lower end of the lever is forked, as at 37, and straddles the stem of the bell-hammer 38. This end of the lever is also made slightly heavier than its opposite end, but not enough

to interfere with the ringing of the bell. To the upper end of the lever a flexible strip 39 is secured, which carries a socket-piece or clamp 40 for a purpose to be described hereinafter.

The drop-shutter is indicated at 41, being hinged, as at 42, at the top of a supporting-plate 43, which is placed on the cleat 27 of the holder 22 and behind the spring-fingers 28, whereby it is securely supported on the holder. A trigger is pivoted in the plate and controls a spring-arm 44, secured to said plate. The trigger comprises two arms 45 and 46, respectively, which extend in opposite direction and are joined by a cross-piece 47, the latter extending loosely through the plate 43. The arm 45 extends downwardly in front of the plate, and the arm 46 extends upwardly behind the plate. The arm 46 has an extension 47, provided with a notch 48, in which the spring-arm 44 is placed and whereby it is held retracted. The spring-arm is located behind the shutter and is arranged to strike the same when released and to cause it to drop forwardly to the position shown by dotted lines in Fig. 2. A slide 49 is dovetailed into a slot in the plate 43, and said slide when removed permits the trigger to be put in position on the plate. The slide is held locked by a latch 50, which is fastened to the edge of the plate and extends over the outer end of the slide. A pin 51 projects from the face of the plate 12 to limit the swing of the trigger-arm 45.

The operation of the device is as follows: The lever 31 straddles the hammer-stem, the upper end of the lever being arranged to extend into the path of the trigger-arm 45. A recess is formed in the plate 12, in which the end of the lever works. The supporting-plate 43 is in position on the holder 22 with the shutter 41 up, as shown in Fig. 1. The spring-arm 44 is placed in the notch 48 and held retracted thereby. When the call-bell rings, the vibrating hammer-stem causes the lever 31 to swing and strike the trigger-arm 45. This causes the trigger-arm 46 to swing also, whereby the spring-arm 44 is released from the notch 48. The spring-arm strikes the shutter and knocks it over against the front of the plate 12, as shown in Fig. 2.

Instead of the shutter a piece of cardboard or slate 52 can be placed on the holder 22, as shown in Fig. 7, the plate 43 and its associated parts first being removed. A pencil 53 is placed in the socket-piece 40 of the lever 31, the pencil being adjusted to contact with the card or slate. When a call is received, the lever 31 swings as before, which causes the pencil to make a dash on the card or slate. The socket-piece is split, as at 54, and is also made tapering, so that the pencil will be securely clamped therein by frictional contact. By reason of the flexible portion 39 of the le-

ver 31 the pencil is made to engage the card or slate with a slight pressure, which is regulated by adjusting the holder 22 to or from the pencil.

The manner in which the device is attached to the door does not interfere with its opening or closing, and it can be fastened without marring or disfiguring the instrument. The device is readily rendered inoperative when so desired by removing the lever 31 from the hammer-stem. This is done by simply loosening the nut 36 and sliding the pivot-screw 75 upwardly in the slot 29 until the lever clears the hammer-stem. As the lever straddles the hammer-stem, there is no danger of the indicator missing a call. The forked end of the lever being slightly heavier than its opposite end, it will hang perpendicular when not in use or when lifted clear of the hammer-stem, thus enabling it to be more readily lowered and adjusted on the hammer-stem.

Having thus described my invention, what is claimed as new, and desired to be secured by Letters Patent, is--

1. The combination with a bell and an indicating device, of a slotted supporting-frame, a pivot-screw adjustably secured in the slot of the frame, and a lever swinging on the screw and engageable by the bell-hammer stem to actuate the indicating device when the bell is sounded.

2. The combination with a bell and an indicating device, of a slotted supporting-frame, a pivot-screw adjustably secured in the slot of the frame, and a forked lever swinging on the screw and straddling the bell-hammer stem to actuate the indicating device when the bell is sounded.

3. The combination with a bell, and a drop-shutter, of a slotted supporting-frame, a pivot-screw adjustably secured in the slot of the frame, and a lever swinging on the screw and engageable by the bell-hammer stem to actuate the shutter when the bell is sounded.

4. The combination with a bell and a drop-shutter, of a spring-arm constructed to strike the shutter to trip the same, a trigger to hold the spring-arm retracted, and means actuated by the bell-hammer stem for operating the trigger to release the spring-arm when the bell is sounded.

5. The combination with a bell and a drop-shutter, of a spring-arm constructed to strike the shutter to trip the same, a trigger to hold the spring-arm retracted, and a lever actuated by the bell-hammer stem for operating the trigger to release the spring-arm when the bell is sounded.

6. The combination with a bell and a drop-shutter, of a spring-arm constructed to strike the shutter to trip the same, a trigger to hold the spring-arm retracted, and a forked lever straddling the bell-hammer stem and actuat-

ing the trigger to release the spring-arm when the bell is sounded.

7. The combination with a bell, of a slotted supporting-frame carrying a drop-shutter, a 5 spring-arm constructed to engage the shutter to drop the same, a trigger to hold the spring-arm retracted, a pivot-screw adjustably secured in the slot of the supporting-frame, and a lever actuated by the bell-hammer stem for

operating the trigger to release the spring-arm 10 when the bell is sounded.

In testimony whereof I have signed my name to this specification in the presence of two subscribing witnesses.

ALFRED LAURENTIUS PETERSON.
